D152,247 S * 1/1949 Flesh D16/245
D160,136 S * 9/1950 Welt D16/245

FIG. 1 is a perspective view of a head to rapidly orient optical or photographic apparatus and the like according to the present invention;
FIG. 2 is a rear view of the head shown in FIG. 1;
FIG. 3 is a front view of the head shown in FIG. 1;
FIG. 4 is a first side of the head shown in FIG. 1 with the handle in a tilted position;
FIG. 5 is a bottom view of the head shown in FIG. 1;
FIG. 6 is a second side view of the head shown in FIG. 1 with the handle in a tilted position;
FIG. 7 is a top view of the head shown in FIG. 1.
